UNITED STATES PATENT OFFICE.

GEORGE B. BARTLETT, OF SOMERVILLE, MASSACHUSETTS.

DESIGN FOR A HASSOCK.

SPECIFICATION forming part of Design No. 29,760, dated December 6, 1898.

Application filed October 22, 1898. Serial No. 694,343. Term of patent 14 years.

To all whom it may concern:

Be it known that I, GEORGE B. BARTLETT, of Somerville, in the county of Middlesex and State of Massachusetts, have invented and produced a certain new and original Design for a Hassock, of which the following is a specification, reference being had to the accompanying drawings, forming a part thereof.

Of the drawings, Figure 1 represents a top view, and Fig. 2 an edge view, of a hassock, showing my design.

The distinguishing feature of my design is the hassock having the shape or configuration shown and comprising a scalloped edge and having a representation of a Maltese cross on its surface. As seen in the drawings, the edge is made up of rounded scallops or divisions, each substantially representing the arc of a circle or, in other words, a gradual o rather than an abrupt curve, there being distinct cusps 22 between the several adjoining arcs. By employing two different shades or colors of material for the top of the hassock, as indicated, the alternate sections are distinguished from each other, there being, as shown, four sections *a* of one shade or color and four intermediate sections *b* of another shade or color, and to further distinguish the sections of one set from those of the other I

make the sections *a* wider than the sections *b*, so that the said sections *a* collectively have the appearance of a Maltese cross with rounded ends. The group of sections *b* lacks this appearance, since their converging ends do not quite meet and are pointed at their inner ends. The radiating edges of the sections *a* are formed by radial straps or welts *c c* between the sections *a* and *b*, these straps or welts being of the same general color or shade of material as the sections *a* and contrasting with the sections *b*. The welts *c c* and sections *a* therefore represent the arms of a Maltese cross, their inner ends being connected, while the sections *b* are narrower than said arms, their inner ends being pointed and separated from each other. At opposite points on the edge of the hassock tabs *d d* are placed, as usual.

I claim—

The design for a hassock, substantially as herein shown and described.

In testimony whereof I have affixed my signature in presence of two witnesses.

GEORGE B. BARTLETT.
